UNITED STATES PATENT OFFICE.

FREDERICK RICHARD SIMMS, OF BERMONDSEY, ENGLAND, AND ROBERT BOSCH, OF STUTTGART, GERMANY.

MAGNETO-ELECTRIC MACHINE.

SPECIFICATION forming part of Letters Patent No. 690,469, dated January 7, 1902.

Application filed September 20, 1901. Serial No. 75,861. (No model.)

To all whom it may concern:

Be it known that we, FREDERICK RICHARD SIMMS, a subject of the King of Great Britain, residing at 55^a Southwark Park road, 5 Bermondsey, in the county of London, England, and ROBERT BOSCH, a subject of the Emperor of Germany, residing at 11 Hoppenlaustrasse, Stuttgart, in the German Empire, have invented new and useful Improvements 10 in Magneto-Electric Machines, of which the following is a specification.

Our invention relates to magneto-electric machines especially intended for use in connection with electric ignition mechanism for 15 internal-combustion engines, and wherein a fixed armature, around which an envelop rotates, is employed; and the object of our invention is to improve the construction of such machines.

According to our invention the envelop is provided with hollow bearings, and the armature is supported in the said hollow bearings, as hereinafter described, and as illustrated in the accompanying drawings, in 25 which—

Figure 1 is a longitudinal section of a machine provided with our improvements. Fig. 2 is an elevation of a detail hereinafter described.

The frame of the machine comprises a bed-plate *a*, having two brackets *b b*, provided with suitable bearings for the envelop to rotate in.

c c are permanent horseshoe-magnets also 35 fixed to the frame.

d is the armature, which in the drawings is shown without its wire windings, and *e* is the envelop inclosing the said armature. This envelop *e* is composed of the cylindrical portion *f*, the end plates *g g'*, and the spindles *h h'*, which are rigidly attached to the said end plates *g g'*, respectively, and rotate in the bearings in the brackets *b b*.

The spindle *h* is hollow or tubular throughout, while the spindle *h'* is only hollow for a portion of its length.

The armature *d* is provided at one end with a spindle *i*, which extends through the tubular spindle *h*, and at the other end with a 50 shorter spindle *i'*, which extends into the aperture in the spindle *h'*.

To the bed *a* is fixed a stud or pillar *j*, the outer end of which is secured to an arm *k*, adapted to receive the end of the spindle *i*, the said spindle *i* and the arm *k* being fitted 55 in such a manner that they can be firmly locked together—for instance, by means of a nut *l*—so as to hold the said spindle *i*, and consequently also the armature *d*, against rotation. The spindle *i* is formed with a longitudinal channel for the passage of the wire-lead *m* to the outside of the apparatus.

The arm *k* may be of the shape shown in Fig. 2—that is to say, it may have a slot *k'* at its lower part, through which the end of the 65 stud *j* passes. By this means the position of the armature can be altered to vary the time of ignition, this being especially useful when starting.

Motion is imparted to the envelop *e* through 70 the medium of the spindle *h'*, upon the outer end of which one of the wheels of the driving-gear (not shown) is fixed. With the construction hereinbefore described it will be understood that the envelop can be rotated while 75 the armature remains stationary, and at the same time the armature is so inclosed as to preclude the possibility of the entrance of dirt or dust.

n n are passages which are provided to allow 80 of the proper lubricating of the parts.

Having now particularly described and ascertained the nature of our said invention and in what manner the same is to be performed, we declare that what we claim is—

1. In a magneto-electric machine, the combination with the field-magnets, of a rotary envelop provided with hollow spindles, an armature within said envelop, provided with spindles extending longitudinally of the hollow envelop-spindles, one of the armature-spindles extending entirely outside of its corresponding envelop-spindle, devices connected to said armature-spindle for holding it and the armature stationary, and means for rotating 95 said envelop, substantially as described.

2. In a magneto-electric machine, the combination with the field-magnets, of a rotary envelop provided with hollow spindles, an armature within said envelop, provided with spindles extending longitudinally of the hol-

low envelop-spindles, one of the armature-spindles extending entirely outside of its corresponding envelop-spindle, adjustable devices connected to said armature-spindle for holding it and the armature stationary, and for adjusting the armature, and means for rotating the envelop, substantially as described.

3. In a magneto-electric machine, the combination with the field-magnets, of a rotary envelop provided with hollow spindles, an armature within said envelop, provided with spindles journaled in the said hollow spindles of the envelop, an arm secured to one of the armature-spindles and provided with a slot

concentric with said spindle, a stationary bolt engaging said slot for holding said armature against rotation but permitting an adjustment of the armature around its axis, and means for driving said envelop, substantially as described. 20
